UNITED STATES PATENT OFFICE

2,180,783

RACKET PRESS

Edric Vredenburg, Jr., London, England

Application October 25, 1937, Serial No. 170,881
In Great Britain October 29, 1936

10 Claims. (Cl. 273—74)

This invention relates to a press for lawn tennis and other games rackets.

An object of the invention is to provide a racket press in which the two co-operating clamping members or frames are connected by toothed rack and detent mechanism to avoid the use of the usual clamping bolts and nuts, and enable a racket to be clamped in the press more expeditiously than heretofore, means being included to release said connections at will for removal of the racket.

Another object of the invention is to provide a racket press as above set forth in which the toothed rack or racks are provided with ratchet teeth, over which the detent or detents slide freely when the clamping frames are approached towards one another, but which are engaged by the detents to prevent the frames being moved apart, so that after insertion of the racket between the frames, a pressure of the hand on one of the frames to force it towards the other is all that is required to clamp the racket and retain it clamped between the frames until it is desired to remove it, whereupon the detent or detents can be released to allow the frames to be moved apart.

A further object of the invention is to provide a racket press as above set forth in which the mechanism is so housed as to avoid projection of any working parts from the outer faces of the press.

Other objects of the invention will appear from the following description taken in conjunction with the drawings, which form a part of the specification.

With these and other objects in view, the invention consists in the construction and novel combinations of parts hereinafter fully described, illustrated by the accompanying drawings, and pointed out in the appended claims, it being understood that various changes in the form, proportion and minor details of construction within the scope of the appended claims may be resorted to without departing from the spirit or sacrificing any of the advantages of the invention.

Several embodiments of the invention are illustrated by the accompanying drawings.

In the drawings:

Figure 1 is a top plan of one form of the press.
50 Figure 2 is a part cross section on the line II—II of Figure 1.

Figure 3 is an end elevation corresponding to Figure 1.

Figure 4 is a perspective view on a larger scale 55 of one of the frame connecting devices.

Figure 5 is a similar view of a modified form of frame connecting device.

Figure 6 is an elevation partly in section of a fragment of the top and bottom frames of a cross type of press with the connecting device at the middle.

Figure 7 is a top plan view of a press of the cross type having connecting devices between each pair of opposed arms, and a device at the middle for operating the connecting devices simultaneously.

Figure 8 is a cross section on a larger scale taken along part of one of the arms of the top frame of the press shown in Figure 7.

Figure 9 is a top plan view on a larger scale, 15 and with the top cover broken away, of the operating device shown in Figure 7.

Figure 10 is an elevation, partly in section, of the cross or end bars of a rectangular press, and alternative connecting means shown on the left 20 and right hand sides of the figure. Fig. 11 is an under plan partly in section of one of the undivided end bars of Fig. 10.

The press illustrated by Figures 1 to 4 comprises two octagonal frames 1, 2 termed for convenience of description a top frame and bottom frames, respectively.

Each frame has a middle bar 3.

The frames are made sufficiently wide to allow a racket head to be slid between them without 30 fouling any connecting parts.

A metal sleeve 4, conveniently of square cross section, is fixed in the top frame 1 at each side. Each sleeve 4 has a longitudinal slot 5.

Two metal rods or rack bars 6 of corresponding 35 cross section to that of the sleeves 4 are fitted in the bottom frame 2.

In the example illustrated, the rods 6 are pivotally supported in brackets 7 to permit of fore and aft play.

The rods 6 slide in the sleeves 4.

They are formed on their inwardly directed faces with downwardly inclined ratchet teeth 8.

The teeth on the sections within the sleeves 4 45 are exposed by the slots 5.

Compression springs 9 are mounted between the frames 1 and 2.

Detent bars 10 are slidably mounted in grooves 11 in the underside of the top frame middle bar 3. 50

The outer ends of the detent bars 10 are bevelled and are pressed into engagement with the teeth of the rods 6 by a compression spring 12.

The spring 12 is arranged between the upturned inner ends 13 of the detent bars, and is 55

housed in a cavity 14 in the middle bar 3, the cavity being closed by a plate or strip 15.

Extensions 16 of the detent bars 10 project through slots 17 in the side of the middle bar 1, 5 and terminate in finger pieces or knobs 18.

Obviously other ways of mounting the detent bars 10 and spring 12 on the frame 1 can be adopted, but the above described or a similar arrangement avoids the projection of working 10 parts from the outer faces of the press.

When a racket head has been slid between the two frames 1 and 2, it is clamped between them by merely pressing them together, or one towards the other, the detent bars 10 slipping freely over 15 the teeth 8 as the frames approach and engaging with said teeth when the applied pressure ceases, so that the frames are held in the clamping position.

Thus, a mere pressure of the hand on the top 20 frame 1, for example, suffices to clamp the racket head between the frames, which are retained automatically in the clamping position directly the hand pressure is removed.

When it is desired to remove the racket from 25 the press, the finger pieces 18 are pressed towards each other to disengage the detent bars 10 from the teeth 8, and the frames 1 and 2 then move apart automatically under the action of the springs 9.

30 In the above example, the frames 1 and 2 are made of wood, but they can be made of metal, in which case the brackets 7 can be dispensed with and the rods 6 can be directly pivoted in the frame.

35 The rods 6 can be formed as ordinary rack bars with plain teeth.

In such case, the detent bars 10 are disengaged from the teeth by the finger pieces 18, as the frames 1 and 2 are moved together, and are released to engage the teeth when the clamping 40 position is reached.

As shown in Figure 5, each sleeve 4 may carry a pinion 19 meshing with the teeth 8—whether ratchet or plain—of the associated rod 6, the detent rod 10 co-operating with the pinion.

45 Two pinions may be employed to mesh with teeth formed on opposite faces of the rod 6, one pinion co-operating with the detent 10 and the other being an idler.

50 In the example illustrated by Figure 6, a single rod and sleeve connection is provided between the two frames 1 and 2 of a cross type of press, at the middle.

55 The rod 6 is provided with ratchet teeth 8 on two opposed faces and the sleeve 4 has opposed slots 5 to expose each set of teeth.

A single detent bar 10 is provided to co-operate with either set of teeth alternately, depending upon which way round the top frame is applied.

60 The detent bar 10 is pressed into engagement with one set of teeth 8 by a spring 12, and can be retracted by a rod 21 with a knob 22 at the end.

To insert the racket, the top frame 1 is removed 65 and the rod 6 is passed through the stringing into the sleeve 4, a protecting washer 23 being threaded on the rod.

Clamping of the racket is effected by merely pressing the frames together or one towards the 70 other, as in the previous example.

By pulling the knob 18 to retract the detent bar 10, the top frame 1 can be removed to release the racket. The rod 6, as in the previous example, may be a plain rack bar.

75 In the example illustrated by Figures 7 to 9,

detent-controlled toothed rod and sleeve connections, as described in the previous examples, are provided between each pair of opposed arms of a cross type of press, together with means for simultaneously retracting the detent bars. 5

A detent bar 10 is provided for each arm and is pressed into engagement with the teeth of its respective rod 6 by a spring 12.

Each detent arm 10 has an upturned end 24, preferably fitted with a roller 25. The upturned 10 ends 24 project into a circular cam casing 26 which is rotatably mounted on a pin 27 secured in the middle of the top frame of the press.

The cam casing 26 is formed with cam faces 28 on its inner wall and its outer wall is preferably milled. The upturned ends 24, or the rollers 25 when provided, bear against the cam faces. 15

By rotating the cam casing, the detent rods 10 are retracted simultaneously from the toothed rods to release the top frame. 20

In the example illustrated by Figures 10 and 11, a rectangular type of press with the frames of normal width has each of the end or cross bars 1, 2 divided, and their meeting ends fitted slidably 25 in a metal sleeve 29.

The meeting ends are held together by a tension spring 30 and each end which may be reduced to fit into the sleeve 29 is provided with a slot 31.

Pins or rivets 32 in the sleeves 29 pass through the slots 31 and so prevent the meeting ends being entirely withdrawn from the sleeves. 30

As shown on the left hand side of Figure 10, the sleeve 29 carries a detent bar 10 for co-operation with a toothed rod 6 on one frame, arranged to slide in a slotted sleeve 4 on the other, as in 35 the previous examples described.

As shown on the right hand side of Figure 10, the frames 1 and 2 carry co-operating square section rods 6, 6' provided with ratchet teeth 8, 8', 40 which are interengaged, the slope of the teeth being such that when the frames are pressed together, the teeth on one rod slip freely over those on the other, but by their interengagement prevent the frames being moved apart.

Springs 9 embrace the rods 6, 6'. 45

In this form of the invention, the connections shown on the left hand side of the figure or the connections shown on the right hand side of the figure can be used on both sides of the press, as desired. 50

With the connections shown on the left hand side of the figure, the frames are merely pressed together or one towards the other to clamp the racket head between them, as previously described, and when it is desired to remove the racket, the press is expanded sideways, so withdrawing the toothed rods 6 away from the detent bars 10, whereupon the top frame is raised by the springs 9.

Similarly with the connections shown on the right hand side of the figure, clamping of the racket between the frames is effected by pressing the frames together or one towards the other, the toothed bars 6, 6' then slipping freely one over the other, the press being expanded sideways to disengage the teeth of the bars 6, 6' and allow the springs 9 to separate the frames, when the racket is to be removed. In this embodiment, the end or cross bars of one frame only need to be made expansible, since the extent of expansion required to separate the interengaged toothed rods is very small. 65

Interengaging ratchet toothed bars such as 6, 6' in Figure 10 can be employed in a press having the frames sufficiently wide to admit a racket. 70 75

head between them without fouling the connections. In such case, for the purpose of separating the toothed rods 6, 6' to permit the frames to be moved apart, one of each pair may be provided with a screw to abut against the other, the screw for the pair on one side being a right-handed screw, and the screw for the pair on the other side being a left-handed screw, the screws being connected by a wire bail which is swung over the press to turn the screws simultaneously and so effect separation of the co-operating toothed rods, which are then mounted with play in the frames to allow of their separation.

The press can be of other shapes than those described, for instance, trapezoidal.

Such a construction will be readily understood by those skilled in the art, without any necessity for illustration.

I claim:

20. 1. A racket press comprising two co-operating clamping frames, a rod provided with ratchet teeth carried by one of said frames and a detent carried by the other frame which is mounted to slide on said rod, the ratchet teeth of said rod being normally engaged by said detent to prevent said frames being moved apart, but permitting said detent to slip over them, when said frames are approached towards one another, thereby enabling a racket to be clamped between said frames by mere hand pressure on one of them, means being provided to disengage said detent from said teeth, at will, to permit of movement apart of said frames for removal of the racket.
35. 2. A racket press comprising two co-operating clamping frames, toothed racks carried by one of said frames on each side thereof and spring pressed detent bars carried slidably by the other frame which is slidably supported on said toothed racks, said detent bars being normally engaged with the teeth of said toothed racks to prevent separation of said clamping frames and means being provided for retracting said detent bars, at will, to permit said clamping frames to be moved apart.
45. 3. A racket press comprising two co-operating clamping frames, a toothed rod having ratchet teeth carried by one of said frames on each side thereof and spring pressed detent bars carried slidably by the other frame which is slidably supported on said toothed rods with said detent bars pressed into engagement with the ratchet teeth of said bars so that said detent bars slip over said teeth when said clamping frames are approached towards one another, and engage with said teeth to prevent said clamping frames being moved apart, means being provided to retract said detent bars from said teeth, at will, to permit said frames to be moved apart.
60. 4. A racket press comprising two co-operating clamping frames, a toothed rod having ratchet teeth carried by one of said frames on each side thereof, bearing sleeves for said toothed rods, carried by the other of said frames, said bearing sleeves having slots therein to expose the teeth of said toothed rods which are slidably mounted in said sleeves, spring pressed detent bars slidably carried by said other clamping frame, to co-operate with the ratchet teeth of said toothed rods, so as to permit said clamping frames to be moved towards one another but to prevent their movement apart, springs between

said clamping frames, and means for retracting said detent bars from the teeth of said toothed bars, at will, to permit said clamping frames to be moved apart.

5. A racket press comprising two co-operating clamping frames, toothed rods having ratchet teeth carried by each of said frames, the teeth of the rods of one frame being interengaged with the teeth of the rods of the other frame and being sloped, so that they slip over each other when said frames are moved together, but interlock to prevent said frames being moved apart, means being provided to separate the engaged teeth, at will, to permit said frames to be moved apart.

6. A racket press comprising two co-operating clamping frames, a toothed rod having ratchet teeth carried by one of said frames on each side thereof, bearing sleeves for said toothed rods, carried by the other of said frames, said sleeves having slots therein to expose the teeth of said toothed rods which are slidably mounted in said sleeves, a pair of detent bars slidably mounted in grooves in said other frame, said detent bars co-operating at their outer ends with the ratchet teeth of said toothed rods, a compression spring mounted in a cavity in said other frame between the inner ends of said detents, normally to press said detents into engagement with the ratchet teeth of said toothed bars to prevent separation of said clamping frames, retracting members provided on said detent bars, and springs arranged between said clamping frames, so that on retraction of said detent bars, said clamping frames are forced apart automatically.

7. A racket press having two co-operating clamping members movable toward and away from each other in a direction transverse to the planes in which they lie, spring-urged detent and toothed rack mechanism with which the spring-urged detent cooperates carried by said press for holding said clamping members in the clamping position, and means for releasing said mechanism at will.

8. A racket press having two co-operating clamping members movable toward and away from each other in a direction transverse to the planes in which they lie, spring-urged detent and ratchet-toothed rack mechanism with which the spring-urged detent co-operates carried by said press for holding said clamping members in the clamping position, and means for releasing said mechanism at will.

9. A racket press comprising two co-operating clamping frames, ratchet-toothed racks carried by one of said frames and sliding in the other, a spring-urged detent for each of said racks, each detent co-operating with the teeth of its associated rack to permit of said clamping frames being moved towards one another, but preventing their movement apart, and means for simultaneously retracting said detents at will, to permit of said clamping frames being moved apart.

10. A racket press comprising two co-operating clamping frames, toothed racks carried by one of said frames and sliding in the other, detents fixed on said other frame for co-operation with said toothed racks to prevent the movement apart of said frames, and means for withdrawing said racks from said detents at will, for separation of said clamping frames.
